UNITED STATES PATENT OFFICE

1,922,691

LOOSE LEAF BINDER

Cyrus E. Morehouse, Clifton Heights, Pa., assignor to National Publishing Company, Philadelphia, Pa., a Corporation of Pennsylvania

Application March 16, 1932. Serial No. 599,177

2 Claims. (Cl. 129—13)

My invention relates to a new and useful loose leaf binder, and it relates more particularly to a loose leaf binder of the "slide bar" type, whereby suitably apertured leaves or sheets are retained upon posts between two flexibly connected bars, to one of which the posts are rigidly secured, and the other of which is detachably secured to the other ends of the posts by means of a slide mounted within said other bar.

10 One of the objects of my invention is to provide a loose leaf binder of this character, of a simplified and more durable construction, which will be dependable in operation and wherein the slide will not become accidentally disengaged.

15 With the above and other objects in view, which will appear more fully from the following detailed description, my invention consists of a loose leaf binder including a pair of flexibly connected covers, a pair of bars, one of which is flexibly or hingedly secured to each of said covers, in proximity to the common back thereof, a plurality of posts carried rigidly by, and projecting at substantially a right-angle from one of said bars, and each having an adjustable head, a plurality 25 of recesses in the other bar in registering alignment with said posts and being adapted to receive said heads and interlocking therewith by engagement beneath the same, and a slide slidably mounted in said latter bar, and operable 30 manually, for locking said post heads within said bar at will.

My invention further consists of other novel features of construction which will appear more fully from the following description.

35 For the purpose of illustrating my invention, I have shown in the accompanying drawings forms thereof which are at present preferred by me, since the same have been found in practice to give satisfactory and reliable results, although 40 it is to be understood that the various instrumentalities of which my invention consists can be variously arranged and organized, and that my invention is not limited to the precise arrangement and organization of the instrumentalities as 45 herein shown and described.

Referring to the drawings in which like reference characters indicate like parts,

Figure 1 represents a perspective view of a loose leaf binder embodying my invention, the same 50 being shown open, with the bars separated, ready to receive suitably apertured sheets.

Figure 2—a represents a bottom plan view of the operating or handle end portion of the upper bar containing the slide, the same being shown 55 with the slide retracted in the unlocked position.

Figure 2—b is a top plan view of the same, in the same condition.

Figure 3—a represents a bottom plan view of the upper bar, with the slide in an intermediate or partly locked position.

Figure 3—b represents a top plan view of the same.

Figure 4—a represents a bottom plan view of the upper bar with the slide in the innermost or 65 fully locked position.

Figure 4—b represents a top plan view of the same.

Figure 5 represents a fragmentary bottom plan view of the opposite end of the slide.

Figure 6 represents an end view of the upper 70 bar, showing the frictional end of the slide which is illustrated in plan view in Figure 5.

Figure 7 represents a section through line 7—7 of Figure 1, on a much enlarged scale, with the binder shown in the locked position.

Figure 8 represents a fragmentary front edge view of the upper bar, with the slide entirely pulled out and unattached to a binding post.

Figure 9 represents a similar view, with the bar attached to the post but not locked thereto.

Figure 10 represents a similar view showing the upper bar locked to the post.

Figure 11 represents a section on line 11—11 of Figure 7.

Figure 12 represents a section on line 12—12 of Figure 11.

Figure 13 represents a perspective view of a modified loose-leaf binder embodying my invention, same being shown open and with the bars 90 separated.

Figure 14 represents a section on line 14—14 of Figure 13.

Figure 15 represents a section taken generally on line 15—15 of Figure 14.

Figure 16 represents a section on line 16—16 of Figure 13 with the bars interlocked, illustrating a further modified construction embodying my invention.

The loose leaf binder of my present invention includes covers 12 and 13, which may be either 100 flexible or stiff, as desired, being flexibly or hingedly connected to each other by means of a back portion 14, which may also be of a flexible or pliable character.

To the bottom cover 13 the bar 15 is flexibly or hingedly secured, as at 16, while to the cover 12, the upper bar, designated generally by the numeral 17, is flexibly or hingedly secured, as at 18.

The bars 15 and 17 are preferably metallic 110

bars, of a hollow, flat, or generally flat tubular construction, formed by folding strips of sheet-metal of suitable thickness. The flat, generally tubular bars 15 and 17 are secured to the covers 13 and 12, by means of the inner lining 19 of the covers, which may be leather or imitation leather, or buckram, or other fabric. Thus, the inner lining 19 is folded about each of the bars in succession, as indicated particularly in Figure 7, with the intermediate portion 20 secured or affixed to the outer lining 21, thereby to form the flexible or pliable back portion 14. In order to insure the binding of the bars 15 and 17, a row of stitches 22 and 23 may be sewn through the two thicknesses of the inner lining 19, along the lines indicated in Figure 7 particularly, so that the bars will be securely encased within said lining, and will thus be hingedly or flexibly secured to the covers.

Two or more hollow tubular posts 24 are mounted in the lower bar 15, in a manner indicated particularly in Figure 7. Thus, the base or flange 25 of each of the hollow tubular posts is disposed between the two parallel and spaced walls of the flat tubular bar, with the post itself projecting through a suitable aperture in the upper wall of said bar. The posts 24 are internally threaded and adjustably carry corresponding screws 26, having heads 27. The heads 27 are of a thickness such as will fit readily between the bottom and top parallel walls of the upper bar 17.

In the lower wall 28 of the upper bar 17, recesses 29 are provided, which enter the bar from the outer edge thereof, and which are in registering alignment with the posts 24. The width of the recesses 29 is slightly greater than the diameter of the screw 26, but sufficiently less than the diameter of the head 27 thereof, and the edge of the upper bar is cut out at 30, sufficiently to clear the head of the screw, so that the head may slide into the bar, or so that the bar may slide onto the screws 26 and heads 27, with the lower wall 28 of the bar 17 interlocking with the heads 27 by engagement therebeneath, as indicated particularly in Figures 7, 11 and 12.

Within the upper bar 17 a slide 31 is slidably mounted, extending substantially the entire length thereof, and having any suitable handle 32 exteriorly of the bar 17, whereby the slide may be moved to and fro.

The slide 31 is provided with a pair of L-shaped recesses 33, corresponding to the posts 24 and in operative alignment therewith, the width of both portions of the L-shaped recesses being slightly greater than the diameter of the head 27 of the screw 26, so that said head may be positioned in any part of the L-shaped recess 33. The L-shaped recesses 33 are disposed in operative relation to the recesses 29 and edge openings 30 in the bar 17, so that when the bar is pulled out to its outer extreme position, indicated in Figures 2—a and 2—b, and Figures 8 and 9, the heads 27 may freely enter the bar 17, through the edge openings 30, with the screws 26 extending downwardly through the recesses 29 in the lower wall 28 of the bar 17, and with the edges of said recesses 29 projecting beneath, and interlocking with the heads 27 of the screws 26.

When the heads 27 have thus entered the bar, or when the bar has thus been slid onto the said heads by a movement generally in the plane of the bar, and transversely of the length thereof, the heads may be locked within the bar by moving the slide 31 inwardly, so that the longitudinal

portions of the L-shaped recesses 33 are juxtaposed to the head, as indicated in Figures 3—a and 3—b, and Figures 4—a and 4—b, and Figures 7, 10, 11 and 12.

The Figures 3—a and 3—b, and 4—a and 4—b show the successive locking positions of the slide.

By this means any force axially of the posts 24, tending to separate the bars 15 and 17, will be borne by the lower wall of the upper bar 17, and will not be borne by the slide 31;—said slide merely serving to lock the post heads within the upper bar.

In order to limit the sliding movement of the slide 31, a stop screw rivet 34 may be fastened into the slide 31, as indicated in Figures 2—b, 3—b and 4—b, with the head of the screw projecting into a generally elongated longitudinal opening 35 in the upper wall of the bar 17; the length of the opening 35 being such as to permit the desired travel of the slide for a clear disengaging and a substantial locking position.

In order further to define the intermediate position of the slide, as shown particularly in Figures 3—a and 3—b, a slight knob or a slightly raised projection 39 may be provided on the slide, which presses against, and frictionally engages the inner surfaces of the lower wall of the bar 17, except when said projection 39 is brought into registering alignment with the clearance opening 40 in said lower wall.

In order to maintain a constant and uniform friction between the slide 31 and the bar 17, the end of the slide 31, opposite to the handle 32, may be split longitudinally to a suitable extent, as at 41, so as to produce two separately flexible springs 42 and 43, which are bent slightly in opposite directions, so that one will bear frictionally against the upper walls, while the other bears correspondingly against the lower walls of the bar 17.

If desired, a stud 44 may also be mounted in the lower bar 15, to project through central apertures or perforations in the loose leaf sheets.

In Figures 13, 14 and 15, is shown a modified construction embodying my invention.

In this form of my invention, rivets 45 are provided extending transversely through the hollow tubular bar 17, without at the same time, interfering with the sliding movement of the slide 31. Means are provided moreover to enable the rivets to serve as limiting stops for the longitudinal movement of the slide.

Thus, according to the present modified construction embodying my invention, spaced, registering apertures 46 are provided on the upper and lower walls respectively of the hollow tubular bar 17, having sufficient diameter to permit the passage therethrough of a suitable rivet 45. A sleeve 47, of slightly larger internal diameter than the external diameter of the rivet 45, is positioned within the bar 17 and about the rivet-receiving apertures; said sleeve being of a length equal to the distance between the upper and lower walls of the bar 17, and having a relatively high compression strength, thereby to support the walls of the hollow tubular bar 17 against collapse when the rivet 45 is headed.

Elongated apertures 48 are longitudinally disposed in the slide 31 generally in registry with said rivet-receiving apertures; said elongated apertures being of slightly larger width than the external diameter of the sleeves 47, and of a length just sufficient to permit the slide to open

and to close, without interference from the sleeves 47.

In Figure 16, I have shown a further modified embodiment of my invention, whereby the split 49 of the hollow tubular bar 17, is disposed in the top wall 50 of the bar 17, thereby to provide a solid beam support for the head 27 of the post 24. In this embodiment of my invention the opening 29 is integral and not composed of two registering apertures, as found in the structure shown in Figures 2—*a*, 3—*a*, and 4—*a*.

I am aware that my invention may be embodied in other specific forms without departing from the spirit or essential attributes thereof, 15 and I therefore desire the present embodiment to be considered in all respects as illustrative and not restrictive, reference being had to the appended claims rather than to the foregoing description, to indicate the scope of the invention.

Having thus described my invention, what I hereby claim as new and desire to secure by Letters Patent, is:

1. A loose leaf binder including a pair of covers flexibly connected through a back portion, a corresponding pair of bars intermediate said covers, connected thereto and extending generally parallel to the back thereof and in proximity thereto, a plurality of posts projecting from one of said bars, having enlarged heads, the other of said

bars having a corresponding plurality of recesses for the reception of the heads of said posts by a relative movement in the plane of said bar, and said latter bar having portions engaging beneath said heads when received within said bar, thereby to engage the said posts in an axial direction with respect thereto, and a slide carried by said latter bar, adapted to close the entrances of said recesses in said bar and to open the same at will.

2. A loose leaf binder including a pair of covers flexibly connected through a back portion, a corresponding pair of bars intermediate said covers, connected thereto and extending generally parallel to the back thereof and in proximity thereto, a plurality of posts projecting from one of said bars, and having members with enlarged heads threadedly carried thereby, the other of said bars having a corresponding plurality of generally transverse recesses for the reception of the heads of said posts by relative movement in the plane of said bar, and said latter bar having portions engaging beneath said heads when received within said recesses, thereby to engage the said posts in an axial direction with respect thereto, and a slide carried by said latter bar, adapted to close and open the entrances of said recesses, at will.

CYRUS E. MOREHOUSE.
